TABULAR CHART SELECTOR

Solomon Diamond, Great Neck, N. Y.

Application November 17, 1941, Serial No. 419,365

5 Claims. (Cl. 235—87)

1

This invention relates generally to tabular chart selectors, that is to devices for locating a predetermined item on a chart on which a number of items are arranged in tabular form in rows and columns. More particularly it relates to devices of this type in which the operator's attention is directed to a predetermined item, as by exposing this item to the view of the operator, while the remaining items are hidden from view.

From one aspect thereof this invention relates to a device of the character mentioned which is adapted for attachment to or incorporation with calculating machines of conventional type and for operation simultaneously with such machines, whereby their range of usefulness is greatly extended since it permits the performance of additional operations together with the regular operations of the calculating machine, as well as the performance of calculations that are not conveniently performed on such a machine, or are impossible of performance thereby.

From another aspect my invention relates to a device for conveniently evaluating a total quantity of a commodity (using this term broadly to include items, both tangible and intangible, that can be evaluated), where the unit rate or rates are also known. A particular application relates to computations in which the unit rate is variable for different quantities so that no uniform proportionality exists between the total value and the quantity, for which reason evaluation of the total on conventional calculating machines is tedious because it requires more than one operation. As examples of such evaluations may be mentioned electric - power consumption charges, income tax computations, social security payments and computations involving wages, where the hourly, daily or weekly rate of compensation is dependent on the duration of the time of employment.

The general objective of my invention is the provision of a selector for tabular charts that is simple, effective, reliable and low in cost and one that will prevent eye-strain attendant on the seeking out of numbers on a chart, minimize eye fatigue due to eye movements across an extended area by restricting and localizing the area to be scanned, eliminate errors due to the human factors and eliminate the necessity for rechecking the computations to discover such errors and thereby effect greater speed in obtaining accurate results.

The more particular objects of my invention include the provision in a device of the character described of means for selecting a predetermined

item in a tabular chart by the interaction of a plurality of mechanisms, one serving to select a portion of the chart within which the said item is located, another serving to select a restricted portion of the chart area selected by the first-named mechanism, and other mechanism or mechanisms still further restricting the selected area, until this area contains nothing but the said predetermined item, which is exposed to the operator's view.

Among the more particular objects of my invention is further the provision in a tabular chart selector of interacting mechanisms for selecting a predetermined item, one of which mechanisms, by way of example, may select the hundreds digit of a predetermined item, another the tens digit, and another the unit digit of said item, where the chart items are arranged in accordance with the Arabic or decimal system of numerical notation.

It is also among the objects of my invention to provide a selector for use with tabular charts having the items thereon arranged in such a manner that they can be produced on typewriters.

A further object of my invention resides in the provision of a selector of the character described which may be attached to or built into a calculating machine of conventional type, so as to be operated thereby when the calculating machine is operated in the conventional manner, and to perform operations adjunctive to those of the calculating machine.

To attain these objects and such further objects as may appear herein or be hereinafter pointed out, I make reference to the accompanying drawing, forming a part hereof, in which:

Figure 1 is a fragmentary view of an example of a tabular chart, the subject of which, for purposes of illustration, is a table of kilowatt electrical consumption and the corresponding charge, the rate for the charge varying irregularly with the quantity, so that no uniform proportionality exists throughout the table between the kilowatts and the charge;

Figure 2 is a fragmentary view of a chart showing the charges taken from Figure 1, arranged in tabular form so as to be suitable for use in the selector device shown in Figure 3;

Figure 3 is a perspective view of a cylindrical type of selector constructed according to the principles of my invention, portions of the exterior casing being broken away to disclose the underlying mechanism, and other portions being omitted for clearness;

Figure 4 is an elevational view on an enlarged

2

scale of the end of the drum or cylinder of the selector of Figure 3;

Figure 5 is a sectional view, also on an enlarged scale, taken through the cylinder of Figure 3 substantially on the line 5—5 of said figure, looking in the direction of the arrows;

Figure 6 is a fragmentary perspective view of one of the stop bars for limiting the position of the drum within a section of ten predetermined rows;

Figure 7 is a fragmentary perspective view of the release bar for releasing the depressed keys of the selector at the end of an operation;

Figure 8 is a fragmentary sectional view, more or less diagrammatic, showing the operating mechanism for the windows overlying the hundreds columns in the selector of Figure 3;

Figures 9 and 10 are fragmentary perspective views respectively of operating mechanisms for selecting the ten rows, and the units rows of the chart on the drum of the selector of Figure 3;

Figure 11 is a perspective view showing a selector similar to that of Figure 3, but suitably modified, attached to a calculating machine;

Figure 11A is a fragmentary sectional view taken substantially on the line 11A—11A of Figure 11, looking in the direction of the arrows;

Figure 12 is a diagrammatic view showing means for effecting the operation of a selector of my improved construction from a calculating machine provided with type wheels;

Figure 13 is a perspective view of another embodiment of my invention in which a flat chart is used;

Figure 14 is a fragmentary plan view of a support and a chart thereon to be used with the selector of Figure 13;

Figure 15 is a sectional view taken substantially on the line 15—15 of Figure 13, looking in the direction of the arrows, parts being omitted for clearness;

Figures 16 and 17 are fragmentary perspective detail views on an enlarged scale, of mechanisms for effecting the selection of limited areas of the chart;

Figure 18 is a fragmentary elevational detail view of other mechanisms for effecting the selection of limited areas of the chart;

Figure 19 is a plan view of a flat chart suitable for use in a further embodiment of my invention, the numbers thereon not indicating the actual items as they would appear on the chart, but being positional numbers;

Figures 20 and 21 are plan views respectively of windowed stencils adapted for superposition on the chart of Figure 19 to perform by their movements, together with the movement of the chart, the operation of selecting a predetermined area on the chart;

Figures 22 to 26 inclusive are plan views showing, on a reduced scale, the chart of Figure 19 and the stencils of Figures 20 and 21 superposed in various relative positions;

Figure 27 is a perspective view of a third embodiment of my invention operating in accordance with the principles explained in connection with Figures 19 to 26 inclusive;

Figure 28 is a fragmentary sectional view, taken substantially on the line 28—28 of Figure 27, looking in the direction of the arrows, and showing mechanism for actuating the chart and the stencils of Figures 19, 20 and 21;

Figure 29 is a fragmentary view substantially along the line 29—29 of Figure 28, looking in the direction of the arrows, of a portion of the mech-

anism thereof, parts being added, and parts being omitted; and

Figure 30 is a fragmentary view, substantially along the line 30—30 of Figure 28 of a portion of the mechanisms of said figure.

Referring now to the drawings in detail, and first of all to Figures 1 and 2, I have shown in the former a chart A having thereon a table comprising pairs of columns *a* and *b*, the first column of each pair comprising in consecutive order, numbers showing the kilowatt hour consumption of electric power, while the corresponding charge is shown in column *b*; for example, the charge for 8 kilowatts is found to be 90 cents, from the chart; and that for 900 kilowatt hours \$32.33.

It will be observed that the charge for a quantity of 0 to 9 kilowatt hours is 90 cents. Thereafter the charge is 6 cents per kilowatt hour until 99 kilowatt hours is reached. Thereafter the charge is 5 cents per kilowatt hour, while from 200 to 999 kilowatts the charge is 3 cents per kilowatt hour. The charge is therefore not in direct proportion to the kilowatt hours throughout the range of the chart.

The columns each comprise one hundred rows, and ten columns are indicated in the chart, whereby provision is made for one thousand items.

In Figure 2, at B, is shown a chart having thereon a table compiled from the columns *b* of Figure 1, that is, it contains only the charges and not the number of kilowatt hours. The items, one thousand in number are shown arranged in ten columns of one hundred rows each, and to show the correspondence of chart B to chart A, 30 these charts have been shown side by side, with corresponding items thereon similarly positioned.

It will be observed that the arrangement of the items on chart B is such that the chart can readily be produced by typewriting, a consideration that 40 is of great practical importance where the rates are frequently changed, necessitating the frequent discarding of old charts and the production of new charts which will be used for only a short time.

45 The selector shown in Figure 3 is intended to function in connection with the chart B of Figure 2, and the problem solved by it is to select a predetermined one of the items shown on said chart. For instance, if it is desired to find the charge for 99 kilowatt hours, the selector will be 50 set, by suitable mechanism to be described, to pick out the corresponding item on the chart, (which is the one hundredth row of the first column *b* of chart A of Figure 1) and on operating 55 the machine the item of chart B corresponding to the ninety-nine kilowatt hours will come into view, while the other items are hidden from view.

Referring now to Figures 3 to 10, inclusive, for 60 a disclosure of a first embodiment of my invention, it will be observed that it comprises a frame or base plate 40 on which are mounted standards 41 and 41a within which a shaft 42 is journaled for rotation, as by a crank 43.

65 Secured to the shaft 42, for rotation therewith, is a drum 44 on which the chart B may be mounted, as by clips 45. Also secured to the shaft 42 is a disk 46, and journaled for rotation in said disk 46 and the end 47 of the drum 44 70 is a plurality of stop bars 48 disposed at spaced intervals along the peripheral portions of the disk 46 and the end 47.

The stop bars 48 are ten in number and each carries thereon a pin 49. The pins 49 are positioned differently for each of the bars 48, as indi-

cated in Figure 6, in which the pin 49 is shown positioned at a point designated by the numeral 4. The other bars 48 have their pins 49 positioned respectively at the points marked 1, 2, 3 etc. in Figure 6, and they are arranged in a series in which the position of the pin 49 of each bar is advanced one position beyond the pin on the preceding bar. This will be apparent from Figure 3 in which the lowermost bar 48 at the front side of the selector has its pin 49 in the 1 position, the bar next above has its pin in the 2 position, the bar next above has its pin in the 3 position and so on.

Each bar 48 is provided with rounded journal portions 50 and 51 and on the end of the journal portion 50 is mounted a squared portion 52 in the head portion 53 of which is mounted a transversely disposed pin 54 which extends outwardly on both sides of the head 53. The pin 54 is disposed at right angles to the pin 49 as well as to the bar 48.

Leaf springs 55, anchored in posts 56, one of which is positioned adjacent the end of each rod 48 (see Figures 4, 6) are carried by the disk 46 and each bears with its free end against one of the squared portions 52 and thereby determines four equilibrium or dead center positions thereof. Stops 57 (see Figure 4) carried by the disk 46 and one positioned adjacent to each pin 54 limit the position of the latter to two of these dead center positions, one of these positions being a radial or active position in reference to shaft 42, and the other an inactive position which is tangential to the periphery of disk 46, and at right angles to the said radial position. The radial position is shown at 54b in Figure 4 and the tangential one at 54a, all the pins except the lowermost one, which is shown in an intermediate position 54c, and the pin at 54b, being shown in the tangential position.

The positions of the pins 49 corresponding respectively to these positions of the pins 54 are shown in Figure 5 and marked 49a, 49b and 49c.

The movement of the pins 54 from the radial position 54b into the tangential position 54a is effected by a stop 58, mounted on the standard 41 (see Figures 3 and 4).

The movement of the pins 54 from the tangential to the radial position is effected by a set of stop levers 59, the nose portions 60 of which engage the pins 49, as will now be explained.

The stop bars 48 are so mounted in disk 46 and drum 47 that when the pins 54 are in their tangential position 54a, the pins 49 will be in their radial position 49a in which they project outwardly. The stop levers 59 are pivotally mounted at an intermediate point 61 thereof on a support 62 (see Figure 3) suitably mounted on the bed plate 40. Below each lever 59 is a key lever 63 pivotally mounted on the bed plate 40, as at 64, and carrying a key 65 at its free end (see Figures 3, 9). A link 66 pivotally secured at one end to the lower end of stop lever 59, as at 66a, and at its other end to the key lever 63, as at 67, serves to transmit movement from the key lever 63 to the stop lever 59. A compression spring 68 normally holds the key lever in its raised position and thereby the nose 60 of lever 59 is kept out of the path of the pins 49. When the key 65 and its lever 63 are depressed, as indicated by the broken line position in Figure 9, lever 59 will move into the broken line position of Figure 9, and its nose will move into the path of one of the pins 49.

The stop levers 59 are arranged in a row and

are spaced laterally from each other corresponding to the spacing of the pins 49 so that the nose 60 of each one of the levers 59 may project into the path of one of the pins 49, and when it does so the lever 59 will engage the pin 49 and will move it, whereby the bar 48 on which the pin is mounted will be turned through 90° and the pin 54 thereon will be turned from a tangential position into a radial position, in which one end thereof projects into a region into which also project a series of stops 69 to be more fully described hereinafter.

It will be observed that the keys 65 are arranged in two banks (see Figure 3) in the conventional manner, because of space considerations.

In order to hold any desired key 65 in its depressed position a detent 70 is provided for each lever 63 which has its nose portion 71 urged against the key lever 63 by a compression spring 72, and when the key 65 is depressed sufficiently the nose 71 of the detent will move over the lever 63 and will hold it in its depressed position, from which it may be dislodged by release of the detent 70 by suitable release mechanism to be hereinafter described.

The stops 69, already mentioned hereinbefore, are in the form of bell crank levers (see Figure 10) pivotally mounted as at 73 on the outer face 30 of the standard 41, and having their nose portions 74 extending through slots 75 in the said standard 41, and into the path of the end portions of the pins 54 when they are in their radial position. The nose portions 74 of the levers are arranged along an arc corresponding to the travel of the said end portions of pins 54 and they are spaced from each other by a distance equal to the width of one of the rows in the chart B, whereby it will be observed that the stops 69, 35 by suitable selection of one of them, may be caused to engage a pin 54, when it is in its radial position and to cause it to stop in any one of ten different positions, each corresponding to one of ten consecutive rows of the chart B, mounted on 40 the drum 44.

For operating the stops 69 selectively, I have shown a bank of keys 76, arranged in two rows to save space (see Figure 3), and each one of these keys is connected to one of the stops 69 by mechanism indicated in Figure 3, and shown more in detail in Figure 10. Said mechanism comprises for each stop 69 a key lever 77 pivotally mounted, as at 78 on the base plate 40 of the selector, and having a key 76 mounted on its free end. A link 55 79, pivotally connected at its upper end, as at 80, to the arm 81 of stop 69, and at its lower end, as at 82, to the key lever 77, serves to transmit movement from the latter to the stop 69, so that when the key lever is depressed into its broken 55 line position of Figure 10 the nose portion 74 of stop 69 will move into its broken line position of Figure 10, in which position it acts as a stop for the pins 54, as already mentioned.

A compression spring 83 acts to hold the key 65 lever 77 normally in its raised position and thereby to hold the nose portion 74 of stop 69 in its inactive position.

A detent 84, having its nose portion 85 pressed against the lever 77 by a compression spring 86, 70 serves to hold the lever 77 in its depressed position when the lever is depressed sufficiently for the nose portion 85 to pass over the upper edge of the lever 77.

To summarize the function of the mechanisms so far described, it will be observed that any de-

sired one of the pins 54 may be brought into its radial or active position and this pin may be caused to stop at any one of the points determined by the stops 69, which determine the position of individual rows on the chart B while each of the pins 54 corresponds to a set of ten adjacent rows, this set being selected by the stops 59, and any desired row of this set is selected by the stops 69. By depressing one of the keys 65 and one of the keys 76 and rotating the drum 44 10 by means of crank 43 in the direction indicated by the arrow in Figure 3 (clockwise as viewed from the left of the figure), the drum 44 will be brought to a stop in a position corresponding to the keys 65 and 76 that are depressed, and which 15 may correspond to any predetermined one of the one hundred lines of chart B.

This predetermined line is brought into registration with a row of windows 87 (see Figures 3 and 8) provided in the housing 88 (which covers substantially the entire selector and which may be arranged to seat on the base plate 40 as shown in Figure 3) which is normally closed by a set of ten shutters 90 which may be selectively moved into open position in which they expose 20 an area of the underlying row of chart B which is equal to the width of one column of said chart, it being understood that this chart is mounted so that each column thereof is in registration with one of said windows.

The shutters 90, as can best be seen in Figure 8, are slidably mounted in the housing 88, for which purpose I have shown rollers 91 between which the shutters are guided, and operable by one or more operating levers 92 which are hinged to the housing 88 at 92a and receive pins 92b carried by shutters 90 in a slot 92c on the free end thereof. A key lever 93, hingedly mounted on the base plate 43 at 94 and carrying a key 95 at its free end, is provided for each shutter 90. A link 96 pivotally connected at its upper end at 97 to the arm 92 and at its lower end at 98 to the key lever 93, serves to transmit movement from the key 95 to the shutter 90. A tension spring 99 acts to hold the levers 92 and 93 in their raised positions and the shutter 90 in its closed position. A detent 100, which may be similar in construction and operation to the detents 70 and 84 already described and shown in Figures 9 and 10, serves to hold each lever 93 in its depressed position when its nose portion rides over the upper edge of said lever.

It will now be clear that by suitable manipulation of the keys 65, 76 and 95, and by turning the crank 43 in the proper direction any desired item on the chart B may be caused to become visible to the operator, though the window 87 while the other portions of the chart are hidden from his view.

For example, if the 839th item on the chart is desired, the operator depresses the key marked "800" in the 95 key set, the key marked "30" in the 65 key set, and the key marked "9" in the 76 key set. He then turns the crank 43 in the direction of the arrow of Figure 3 until the stop 69 that was projected by the "9" key prevents further turning. In the window 87 that was opened by the depressed "800" key, which raised the eighth shutter 90, he then sees the 839th item, which in the case of the kilowatt hour chart shown in Figure 2, would be the charge for 839 kilowatt hours of electricity.

To render the selector available for the next operation, a release mechanism is provided. This is shown by way of example in Figure 7 as a rod 103, mounted for sliding movement on the base

5 plate 40 or other fixed part of the selector, and provided with arms 104, each adapted to engage one of the detents (70, 84 and 100) so that when the rod 103 is slid the detents will be moved to cause them to release the key levers. The detent springs serve to cause the rod 103 to return to its initial position. A head or button 105 (see Figs. 3 and 7) serves for manipulation of the rod 103.

10 If desired, obviously, a separate release may be provided for each one of the sets of detents 70, 84 and 100.

15 It will now be understood that after the desired reading has been obtained the keys will be released and then set for the next reading, which is obtained by again turning the crank 43 in the appropriate direction. The stop 58, it will be observed, serves automatically to reset the pin 54, previously set into its radial position 54b for the previous reading, into its tangential position upon striking engagement occurring as a result of turning of the crank 43, as above indicated.

20 The arrangement of items on chart B of course may take forms other than those illustrated. The selection of the vertical columns for the "hundred" has some advantages for the kilowatt hour chart where most of the kilowatt hour figures lie within a small range (say, up to 199), since it reduces the eye movements of the operator, but obviously other considerations might call 25 for other arrangements. For example the columns might be arranged for the units so that numbers from 0 to 9 would read across the chart on the first line. The other keys instead of being tens and unit keys would then be hundreds and tens keys.

30 The device just described is intended for manual operation. In Figures 11 and 12 I have shown means to effect operation of the selector automatically from a calculating machine. At the same time, if desired, as indicated in Fig. 11, the machine is also provided with keys for manual operation, which may be carried out on the machine in lieu of the automatic operation. Means 35 to effect the latter is shown in Figure 12. Instead of the crank 43 of Figure 3, a motor drive has been shown to effect the rotation of the chart.

35 In Figure 11 a calculating machine of standard type is shown at 110 and on the shelf 111 thereof 40 is shown positioned a selector 112 of my improved type, which is electrically connected through the cord 113 with the machine 110, which in turn, is connected to a source of electricity by a cord 114. The selector 112 is shown as driven 45 by a motor of any suitable or preferred type continuously running in the same direction, which transmits movement to the selector 112 by a suitable arrangement, such as the slip clutch arrangement shown in Figure 11A. In this figure 50 the main shaft of the selector is shown at 42' and keyed thereto is one member 112b of a friction slip clutch, the other member 112c of which is mounted for sliding movement on, but held 55 against rotation relatively to the shaft 112d of the motor 112a, and is urged against the member 112b by a spring 112e which permits slipping of the clutch members 112b and 112c relatively to each other when the resistance to movement of shaft 42' exceeds a predetermined limit.

60 In Figure 12 one of the type wheels of the machine 110 is shown at 115. In fixed relation thereto, so as to rotate therewith is shown a commutator arrangement comprising a set of brushes 116 mounted to rotate with the type wheel 65 115, and spaced circumferentially so that each 70

75 116

one corresponds to one of the characters on the type wheel, and to one of the keys of the selector 112. Only two of these brushes (of which ten are required) have been shown, as that is sufficient to explain the action of the entire arrangement.

A fixed insulating disk 117 has a conducting bar 118 therein which is connected through conductor 119 to one side of a source of electricity 120, to the other side of which are connected, through conductors 121 the solenoids 122, each adapted, when energized, to render operative one of the keys 123 of the selector. The other side of each solenoid 122 is connected by conductors 124 diagrammatically shown to one of the brushes 116 by means of usual commutator arrangements, not shown. A switch 125 is interposed between the source 120 and the bar 118, and this is adapted to be closed whenever the totaling device of the machine is operated, as by a rod 126 moved by said totaling device. As the type wheel 115 turns the brushes 116 are consecutively brought into contact with the conducting bar 118, and on each contact a circuit is established, serving to energize that one of the solenoids 122 that is connected to the contacting brush, and thereby one of the keys 123 is rendered operative, as soon as the switch 125 is closed through the operation of the member 126 by the totaling mechanism of the calculating machine.

Obviously instead of the electrical connection shown by way of example other types of connection, such as direct mechanical connection, may be used.

On the other hand instead of the direct mechanical connections of the keys, remote control may be used therefor, such as one resembling the electrical arrangement of Figure 12. This would permit greater flexibility in the grouping of the keys to secure greater efficiency without necessarily complicating the mechanism.

It will be understood that in addition to more effective arrangements of the keys, the various sets of keys may be distinguished from each other by color or by configuration or in other ways, so as to minimize the chance of error by striking the wrong key.

In the embodiment of my invention shown in Figures 13 to 18, use is made of a chart C (see Figure 14) which may be identical with the chart B of Figure 2, but which is mounted flat on a flat slide 130 which is arranged for sliding movement in guideways 131 mounted on the frame of the machine, which is of suitable construction and configuration, the details thereof not being comprehensively shown, other than the bed-plate 132.

The guideways 131 are preferably of the frictionless type, such as the ball-bearing type, which might include balls such as shown at 133 in Figure 16 in broken lines, which are mounted on the guideways 131 and engage grooves 134 provided in lateral extensions 135 of the slide 130.

A counterpoise arrangement of conventional type may be provided (see Figure 15) to counterbalance the weight of the slide 130, where the latter is mounted, as shown in Figures 13 and 15 for movement approaching the vertical. This counterpoise is shown in Figure 15 as of the spring type, comprising one or more coil spring actuated spools 136 on which are wound straps 137 which are led over suitably disposed guide rollers 138 and which have their free ends connected to the slide 130. The springs are so arranged that they will tend to wind up the straps 137 and thereby

raise the slide 130. The tension of the springs is however insufficient to overbalance the weight of the slide 130, so that when the same is released it will tend to move downwardly.

The slide 130 is provided with thumb pieces 139 which protrude through slots 140 in the walls of the housing 141 which encloses the mechanism of the selector and which seats on the base-plate 132. The thumb-pieces 139 serve for raising the slide 130 into its initial position, which is also its uppermost position, and hooks 142 are provided at the top of the slide (see Figure 14) which are adapted to engage hooks 143 on a bar 144 (see Figure 13) which is mounted for transverse sliding movement in the top of the housing 141. This bar 144 is urged to the right, as seen in Figure 13, by a spring 145, which engages a lug 146 on the bar. When the bar is pushed to the left, as by manipulating the thumb-pieces 139 on the bar, the hooks 143 also move to the left and become disengaged from the hooks 142 on the slide 130, whereby the latter is released and moves down.

The downward movement of the slide is limited by a system of stops, which in general are similar to the stops of the embodiment of Figure 3, and which determine the row of the chart C on which the desired item is located. As in the embodiment of Figure 3 a set of windows is used to select the desired column.

The windows 148 are shown in Figures 13 and 17 and the details of the operating mechanism therefor are shown in Figure 17. Ten windows 148, arranged in a row, are provided, and a shutter 149 normally closes each window, but may be opened by manipulation of a key 150, these keys being arranged in a row, as shown in Figure 13. The shutters 149 are flat strips (see Figure 17) suitably mounted for sliding movement as in grooves indicated at 151. A key lever 152 of bell crank type, carrying a key 150 at its free end and pivoted at 153, is provided for each shutter 149. The end of the short vertical arm 154 of the lever 152 engages one end of the shutter 149 and as the key 150 is depressed the shutter 149 is drawn to the right, as shown in Figure 17, and the window is opened.

A tension spring 155 tends to hold the key 150 in its raised position and the shutter 149 in its closed position. A detent 156 is provided, the nose 157 of which is urged against the lever 152 by the tension spring 158, and is adapted to ride over the upper edge of said lever when the lever is sufficiently depressed, and to hold it in its depressed position until released from the detent. For the latter purpose a release is provided, which may be of the type shown in Figure 7 and which is indicated at 159 in Figure 13.

As in the embodiment of Figure 3 the shutters 149 preferably select the hundreds, which are accordingly arranged in vertical columns on the chart C, each of which moves under one of the windows 148.

The selection of a particular row on the chart C is effected by two sets of stops, one determining ten consecutive rows and the other determining a particular row of this set of ten consecutive rows. The first-mentioned stops will therefore be the "tens" stops and the others the "units" stops.

The "tens" stops are manipulated by a set of ten keys 160 each carried on the end of a lever 161 (see Figure 15) pivotally mounted, as at 162, on the frame of the machine, urged upwardly by a tension spring 162a, and serving by means of a link 163, pivotally connected thereto at 164, to actuate a bell crank lever 165, pivotally mounted

on the frame of the machine at 166, to one arm of which bell crank lever the link is pivotally connected at 167. The free end 168 of the other arm of the lever 165 acts as a stop for a pin 169 carried by the back of the slide 130, and shown in Figure 15 and in greater detail in Figure 16.

One pin 169 is provided for each lever 165 and is positioned in alignment therewith. The pins 169 correspond to the pins 49 of the embodiment of Figure 3, and the levers 165 correspond to the levers 59 of said embodiment. As will be observed from Figure 16, each pin 169 is carried by a rod 170 pivotally mounted on the back of the slide 130 and running transversely thereof. The rods 170 are mounted parallel to each other and are spaced from each other a distance corresponding to the vertical distance covered by ten horizontal rows on the chart C and they are provided with squared portions 170a engaged by leaf springs 170b whereby four equilibrium positions are secured, this construction being similar to that shown in Figure 6, and already described hereinabove (parts 52, 55, 56). The pins 169 are offset from each other in a horizontal direction, the horizontal distance between them corresponding to the spacing of the levers 165 and the positioning being such that the nose portion 168 of one of the levers 165, when said nose portion is depressed by the key 160, is in the path of the free end portion of one of the pins 169, when the pin is in a position projecting outwardly from the slide 130 such as the position shown for the uppermost two pins 169 in Figure 16, which pins are numbered 169a and 169b respectively.

Five levers 165 are shown in Figure 16, the four shown in broken lines being numbered 165a, 165b, 165c and 165d respectively, while the fifth one is shown in full lines and numbered 165. This latter lever is shown in its depressed position, and the pin marked 169 has just passed the nose portion 168 of the lever 165 and has been moved through 90° so that it no longer projects outwardly from the slide 130. In doing so it has turned the rod through 90°.

The levers 165a and 165b are shown in their raised position so that they will permit the pins 169a and 169b to pass without moving them as the slide continues its downward movement. If depressed, however, the lever 165a would engage the pin 169a and the lever 165b would engage the pin 169b and these levers would move the respective pins so as to rotate the rods 170.

On the end of each rod 170 is positioned a transverse pin 171 which is at right angles to the pin 169, and changes its position together with the pin 169. When the pins 169 are in their position as shown at 169a in Figure 16 in which they project outwardly from the slide, the pins 171 will lie in the direction of movement of the slide 130, and this position is their inactive position.

Pins in this position are marked 171a and 171b in Figure 16. The lowermost pin 171 in Figure 16 has assumed a position at right angles to the direction of movement of the slide 130 because of the turning through 90° of its rod 170 effected by the engagement of the nose portion 168 of the lever 165 with the pin 169. This is the active position of the pins 171. As the slide continues the downward movement the pin 171 which is in its active position will engage a stop 172, shown in full lines in Figure 16, which is one of a set of ten stops (see Figures 16, 18) selectively controlled by a set of ten keys 173 (see Figures 13, 18). The stops 172 are in the form of slidable flat rods arranged parallel to each other in a

suitable support 174, and are adapted by the keys 173 to be selectively protruded into the path of the pins 171 as the slide moves downwardly, when said pins are in their position at right angles to the direction of movement of the slide 130.

The stop 172 shown in full lines in Figure 16 is in its protruded or active position, while the other stops 172 shown in broken lines, are in their retracted or inactive position. When an active stop 172 engages an active pin 171 further downward movement of the slide 130 is prevented. In this manner it will be observed that the vertical position of the slide 130 may be controlled so that any desired row of the chart C may be brought to the level of the windows 148.

For controlling the stops 172 I have shown a set of key levers 175 each pivotally mounted at an intermediate point thereof in the bed-plate 132 at 176 and carrying a key 173 at one end thereof while to the other end is pivotally attached as at 177, one end of a link 178, the other end of which is pivotally secured at 179 to one of the stops 172. A tension spring 180 urges the key 173 into its raised position, which corresponds to the retracted position of the stop 172. When the key 173 is depressed the lever 175 will assume its broken line position and the stop 172 will be projected as indicated in broken lines at 172a in Figure 18.

To hold the keys 160 and 173 in their depressed positions I have shown detents 181 and 182 respectively, each associated with one of the key levers. These detents may be of the type shown at 153 in Figure 17 and may be moved into their released position by a control rod indicated at 183 in Figure 13, and which may function like the rod 103 of Figure 7.

In order to reset the pins 169 into their inactive position stops 185 have been shown in broken lines in Figure 16. These are pivoted to the frame of the machine at 186 and are pivotally connected to a rod 187, pulled downwardly by a spring 188, but this movement is limited by stops 189, one of which is associated with each rod. When the slide 130 is moved up into its starting position the stops will engage the outer ends of any pins 171 that are in their active position and will restore them to their inactive position.

It will be observed that the functioning of this embodiment of my invention is substantially the same as that of the embodiment of Figure 3, the hundreds being controlled by keys 150 which control the windows 148, while the row is selected by the tens keys 160 and the units keys 173.

After an initial setting of the slide 130, accomplished manually by raising the slide by means of the thumb pieces 139 until the hooks 142 and 143 interengage the keys are manipulated for the desired setting, and the slide is released by the moving bar 144 by means of the thumb-pieces 147, after which the slide automatically moves into its desired position, and the predetermined item appears at the window 148 that has been opened by the keys 160.

In Figure 19 I have shown a chart D which is arranged on a different principle from the charts B and C. It is divided into ten sections of one hundred items each, which have been lettered d, e, f, g, h, i, j, k, l and m. They are arranged on the chart in two columns of five sections each, and each section has ten columns and tens rows of items. These items have been numbered consecutively, in the drawings, the numbers therefor indicating not the actual item, but merely the

position of the item in relation to the operation of the machine.

The numbers in each section begin at the upper left hand corner and continue horizontally across the row and then continue beginning with the first item on the left of the next row. For instance, in section *a*, the first number at the left of the first row is 000 while 001 is found to the right of this and 009 at the end of the first row. The second row commences with 010 and ends with 019, while the third row commences with 020.

To give another instance, the section *k* commences with 700 on its first row, which ends with 709, while its last row commences with 790 and ends with 799, which also marks the end of the section.

The order in which the sections are arranged follows their lettering. Section *d* commences with 000 and ends with 099, and section *e*, on the same line, commences with 100 and ends with 199. The next section commences with 200 and ends with 299, and so on.

For selecting any desired item, I make use of two stencils, one being shown at 200 in Figure 20, and the other being shown at 201 in Figure 21.

The stencil 200 has a set of ten windows 202 provided therein, each of a size to expose one of the items of chart D, and these are arranged in two columns. The windows are spaced from each other so that the distance *p*—*q* in Figure 20 is equal to the horizontal width of one of the sections of chart D, while the distance *p*—*r* is equal to the vertical height of one of said sections, so that the rectangle *p*—*q*—*r*—*s* is identical in configuration and area with one of said sections. It follows that when the stencil 200 is superposed in appropriate position, on the chart, that is with its rows parallel to those of chart D, the items visible through its windows will be corresponding items in all the sections. For example if item 001 appears at the uppermost left hand window, item 101 will appear at the uppermost right hand window, and the other windows will show items 201, 301, 401, 501, 601, 701, 801 and 901 respectively. When the chart D is shifted to the left relatively to the stencil 200, a distance equal to the width of one column, the item number increases by one; when it is correspondingly shifted to the right the item number decreases by one.

If the stencil 200 is moved down over the chart D through a distance corresponding to one row, the item increases by ten; when it is moved in the opposite direction it decreases by ten.

The stencil 201 has ten windows 203 therein, each of a size to expose ten vertically consecutive items and these are arranged in two laterally spaced staggered columns. The spacing of the columns is such that the rectangle contained within the two uppermost windows and the broken lines in Figure 21, and which is determined by the points *t*, *u*, *v* and *w* of said figure is identical in height and width with one of the sections of chart D.

The lateral horizontal displacement of the windows 203 is equal to double the horizontal width of one of the windows 202 or to double the horizontal width of one of the items of chart D. The bottom of one row of windows 203 is on a level with the top of the next row.

If the stencil 201 is appropriately superposed on the chart D with its rows parallel to the rows of chart D, then when the item 000 appears at the top in the uppermost left hand window the up-

permost right hand window will show item 009 at its top. The second row of windows will show no item in the left hand window and will show item 207 at the top in its right hand window. The left hand window of each of the remaining rows will be blank, and the right hand window will show respectively items 405, 603 and 801 at the top.

If now stencil 200 is superposed over stencil 201 with the rows thereof in parallel relation to each other, it will be found that only one window 202 at a time can be brought into registration with a window 203, and therefore only one item at a time of the underlying chart D will be exposed through the two stencils.

By an arrangement to be described hereinafter the chart D and the two stencils 200 and 201 are mounted in a support for movement therein, the chart D for sliding movement in a horizontal direction, the stencil 201 overlying the chart D also for movement in a horizontal direction, and the stencil 200, overlying the stencil 201, for movement in a vertical direction.

The effect of relatively moving the chart and the stencils will be understood by reference to Figures 22 to 26 inclusive.

In Figure 22 the chart D is in its extreme right hand position, the stencil 201 is in its extreme left hand position and the stencil 200 in its extreme uppermost position. The item 000 appears in the uppermost left hand window.

In Figure 23 is shown the effect of moving the stencil 201 to the right by a distance equal to the horizontal width of one item. The item increases by 100, so that 100 appears at the uppermost right hand window 202 and no other item is exposed. If the stencil 201 is shifted to the right by another distance equal to the horizontal width of one item, the item 200 is the next to appear in the left hand window of the second row. In the same way by stepwise movements of the horizontal width of one item the items 300, 400, 500, etc. appear, each at another window, until the item 900 appears at the lowermost right hand window. This marks the limit of movement of the slide 201 to the right.

If from the position of Figure 22 chart D is moved to the left by a distance equal to the width of one item, the item number is increased by one, as can be seen from Figure 24, in which item 001 appears at the upper left hand window.

Further stepwise movement of the chart D to the left will successively expose items 002, 003, 004 etc. until item 009 is reached which marks the extreme limit of movement of chart D to the left.

If the stencil 200 is moved downward from its position of Figure 22 in a vertical direction by the vertical height of one item, the item will increase by ten, and further stepwise movement will result in successive increments of ten. The limit of movement of the stencil 200 is ten such steps so that if in Figure 22 it reaches its bottom position the item 090 will be exposed in the uppermost left hand window 202.

The effect of simultaneous movements of the chart and the stencils is shown by way of example in Figures 25 and 26.

In Figure 25, the stencil 200 has been moved down nine steps, the chart D has been moved to the left five steps and the stencil 201 has remained in the position of Figure 22. The item 095 appears in the uppermost left hand window 202.

In Figure 26 the stencil 200 has been moved down nine steps, the stencil 201 has been moved

to the right five steps, and the chart D has been moved to the left four steps, so that the item 594 appears at the extreme right hand window of the middle row.

It will be observed that the arrangement of the windows in the stencils 200 and 201 is peculiarly coordinated to the arrangement of items on the chart D so that by predetermined movements, following a convenient order, of the stencils and the chart, any predetermined item of the chart will be exposed. It will further be observed that by providing a plurality of stencils having a plurality of windows in each the necessary movements of adjustment are reduced in extent, whereby speed and convenience are gained.

In Figure 27 I have shown an embodiment of my invention in which the chart D and the stencils 200 and 201 are assembled in a form convenient for manipulation.

The outer casing or housing 205 which covers substantially the entire mechanism, is provided with a window 206 through which the stencil 200 is visible, so that the items of the chart D are visible through its windows 202.

In Figures 28, 29 and 30, details of the mounting of the stencils 200 and 201 and the chart D, and the mechanism for moving them are shown. The chart D is shown mounted for horizontal movement along guideways 206 and 207, which may be of the ball-bearing type provided with balls 208, while the stencil 201 is similarly mounted for horizontal movement on guideways 209 and 210 provided with balls 211.

The chart D is provided with teeth 212 (see Figure 30) meshing with the teeth of a spur gear 213, which is mounted on a shaft 214 on which is also mounted a bevel gear 215 which meshes with the bevel portion 216 of a combined bevel and spur gear, the spur gear portion 217 of which meshes with a rack bar 218, shown in cross-section in Figure 29. This rack bar is one of a set of three comprising the rack bars 218, 219 and 220, all shown in section in Figure 29, the rack bar 220 shown in elevation in Figure 23. These rack bars may be extensions of or be connected to the type bars of a calculating machine, or they may be manually controlled as by adjusting knobs 221, 222 and 223 (see Figure 22) suitably connected thereto. Indicating windows may be provided as shown at 224, 225 and 226 in Figure 22, the numbers appearing in each one of these being determined by one of the bars 218, 219 and 220. This number would be the positional item number (for instance the number of kilowatt hours where the chart is a kilowatt hour chart) while the number appearing in the windows 202 would be the desired item of the chart.

The stencil 201 is provided with rack teeth 221 (see Figures 28 and 30) which mesh with the teeth of a spur gear 228 mounted on shaft 229, which also carries a bevel gear 230. The latter is driven by the bevel portion 231 of a combined bevel and spur gear, the spur gear portion 232 of which is actuated by the rack bar 219.

The stencil 200 is mounted for sliding in a vertical direction, for which purpose paired guide rollers 233 and 234 are shown between the upper pair 233 of which the stencil 200 slides, while between the lower pair 234 an extension 235 provided with rack teeth 236 slides. The teeth 236 mesh with a pinion 237 which is actuated by the rack bar 220.

In Figure 29 the combination bevel and spur gears 216—217 and 231—232 and the pinion 237 are shown mounted on a stub shaft 238. It will

be understood that they are operable independently of each other and that therefore not more than one may be keyed to the shaft while the others are free to rotate thereon; of course all of them may be mounted to rotate on the shaft.

The operation of the embodiment of Figures 27 to 30 may be briefly summarized by stating that the position of the chart D and the stencils 200 and 201 is adjusted by means of the rack bars 218, 219 and 220 so that the desired item appears in one of the windows 202 in accordance with the principles explained in connection with Figures 19 to 26. The rack bars may be controlled either from a calculating machine by direct or indirect connection to the type bars or other totaling mechanism thereof or by remote control therefrom, or they may be controlled manually by controls such as the knobs 221, 222 and 223.

It will be understood that the various elements of the selector mechanisms may be used in combinations other than the exact combinations shown and described.

While I have herein disclosed several illustrative embodiments of my invention, it will be understood that the same may be embodied in many other forms without departing from the spirit thereof, as will be obvious to those skilled in the art. It will further be understood that the disclosure herein is by way of illustration merely and is not to be interpreted in a limiting sense, and that I do not limit myself other than as called for by the language of the appended claims.

Having thus described my invention and illustrated its use, what I claim as new and desire to secure by Letters Patent is—

1. In combination with a unitary tabular chart having items thereon arranged in rows and columns, each of said items corresponding in position to a definite quantity of a commodity and corresponding in magnitude to the value of said definite quantity of the commodity, and the rate on which said value is based being different for different quantities of the commodity so that there is no proportionality between the quantity and the value throughout the range of quantities covered by the chart, the combination therewith of a mounting for said chart whereby it is movable, stop means for said chart mounting means including key operated means for controlling the movement of the chart mounting means to a predetermined position, a member for shielding the chart provided with a plurality of windows through any one of which a single one of the items of said chart may be seen, each window being associated with a definite portion of said chart so that a predetermined item can only be seen through the particular window which is associated with that portion of the chart in which the item is located, a movable closure associated with each window to unmask or to mask the window, means for selectively moving any one of the closures into its unmasked or its masked position, and visible indicia bearing control means cooperating with co-acting stop means on the mounting means of said chart for predeterminedly moving the chart and positioning that portion of the chart on which a predetermined item is located to a position corresponding to a selected definite quantity of a commodity so that said predetermined item is in registration with that window which is associated with the portion of the chart on which the predetermined item is located whereby when a selected movable closure is operated by the selective means therefor, the item of corresponding magnitude as to value may be

viewed, to the exclusion of other items on the chart.

2. A selector comprising a frame, a rotatable cylindrical support on said frame, a tabular chart on said support having items thereon arranged in rows extending axially of the support and in columns extending circumferentially of the support, a first set of stops in a common plane movably mounted on said support for selective movement into an operative position and spaced circumferentially thereof at intervals corresponding to a predetermined number of rows of the chart, a second set of stops on the frame, each stop being mounted for selective movement into an operative position in which it protrudes into the path of a selected one of said first set of stops when it is in its operative position, the number of said second stops corresponding to the said predetermined number of said rows and said stops being spaced circumferentially relatively to said support and spaced apart distances corresponding to the distances between rows of said charts, means for selectively bringing any one of the stops of the first set into its operative position, and means for selectively bringing any one of the stops of the second set into an operative position in which it protrudes into the path of said operative stop of the first set.

3. A selector for tabular charts having items thereon arranged in rows and columns, a chart, a support for said chart, a mounting for said support whereby it is movable rectilinearly, a stencil provided with a plurality of windows, a mounting for said stencil whereby it is movable over said chart rectilinearly in the same direction as said support, a second stencil overlying said first stencil and provided with a plurality of windows, a mounting for said second stencil whereby it is movable rectilinearly in a direction at right angles to the movement of the other stencil, the windows of the second stencil being disposed relatively to the windows of the first stencil so that only a single window of each stencil may be brought into registration at one time with a single one of the windows of the other stencil, and means for selectively moving said chart and either of said stencils from the totaling mechanism of a calculating machine.

4. In a selector for selecting an item on a tabular chart having items thereon arranged in rows and columns, a base, a support for said chart mounted for movement on said base in the direction of the columns thereof, a set of stops on said support, a second set of stops on said base, the stops of said two sets being arranged for coaction to determine the position of said support and

means on said base for selectively causing coaction of any stop of one set with any stop of the other set, whereby said support may be brought to a stop in any one of a number of positions, the number of said positions being equal to the product of the number of stops in one set and the number of stops in the other set.

5. In combination with a selector as set forth in claim 4, apertured means for concealing said chart from the view of an operator, closure means for each of the apertures in said concealing means, and means for selectively rendering any one of said closure means ineffective whereby the portions of the chart registering with the corresponding aperture will be visible to the operator, said apertures being arranged in a row disposed transversely to the direction of movement of said support whereby the portion of the chart visible through a predetermined aperture is a strip having the width of the aperture, whereby the number of individual predetermined areas of the chart that may be exposed to the view of the operator is equal to the aforementioned number of positions of said chart multiplied by the number of said apertures.
